(57) **CLAIM**

The ornamental design for a light diffuser, as shown and described.

DESCRIPTION

FIG. 1 is a front, top perspective view of a light diffuser showing the new design;

FIG. 2 is a front, bottom perspective view thereof;

FIG. 3 is a front elevation view thereof, wherein the rear elevation view appears the same in mirror image;

FIG. 4 is a side elevation view thereof, wherein the opposite side view appears the same in mirror image;

FIG. 5 is a top plan view thereof; and,

FIG. 6 is a bottom plan view thereof.

The broken lines showing in the drawings are included for the purpose of illustrating portions of the light diffuser that form no part of the claimed design. The dash-dot-dash line depicts the boundary of the claim.

1 Claim, 6 Drawing Sheets
